1 Claim. (Cl. 24—3)

The present invention relates to a device for attaching articles to a support and has for its principal object to provide at a low price a device whereby an article can be attached simply to a wall, a pillar, fixture, furniture, or the like.

The principal object of the present invention is to provide an economically producable device for attaching articles to a support and which can be used for retaining a variety of articles.

Further and other objects and features of the present invention will be made clear from the following explanation of the embodiments shown on the accompanying drawings, wherein:

FIG. 1 is a perspective view of an attaching device according to the invention.

FIGS. 2 and 3 are perspective views showing manners of use of the embodiment shown in FIG. 1.

Referring now more particularly to the drawing there is shown a base member 1 which comprises a film of a flexible, synthetic resin such as vinyl, nylon, vinylon, polyethylene or others. The back surface of said base member is coated with a cohesive or adhesive agent 2, and the adhesive surface is applied with an easily removable separator 3 such as paper coated with a parting agent or cellophane.

There is also provided a spring clip 4 which has a ring shaped base 5 through which extends the medial portion 6 of a holding sheet 7 of flexible synthetic resin. Said holding sheet 7 has marginal end portions 8 and 9 connected solely along a lateral line thereon, to the front face 10 of said base sheet 1, by a suitable adhesive with the remaining portions of said holding sheet being free. This device is used for hanging a curtain, hanging an article from a ceiling, displaying goods or otherwise.

FIGS. 2 and 3 show the manners of use in the cases

2

when the embodiment of FIG. 1 is used as a curtain hanger A and is attached to a ceiling B, respectively. In the case when the same is used as a curtain hanger as in FIG. 2, the base member 1 is folded in two for holding therebetween an edge of a curtain A, and spring clip 4 is clipped onto a curtain rod C.

Each embodiment will be more effective for advertisement purposes if company's name, names of products or others are printed thereon.

I claim:

10 An article attaching device comprising a base sheet of a pliable synthetic resin, a coating of an adhesive on one face of said base sheet for adhering to a supporting surface, a holding sheet of a flexible synthetic resin being folded at its medial portion and having its marginal end portions connected solely along a lateral line thereon to the other face of said base sheet and the remaining portions of said holding sheet being free and a spring clip having a base ring with the folded portion of said holding sheet 15 extended therethrough pivotally connecting said spring clip to said holding sheet.
